MATCH HOLDER

Marvin I. Karp, New York, N. Y.

Application October 31, 1945, Serial No. 625,786

12 Claims. (Cl. 206—48)

1

This invention relates to novel match pack holders and more particularly to a compactly collapsible match packet holder which may be readily placed in releasable firm engagement with a package of cigarettes or tobacco.

Various devices have been proposed for maintaining a pack of matches in association with a cigarette package. However, such devices have generally been bulky, inefficient in operation, incapable of firm securement to a cigarette package and complicated in construction.

It is among the objects of the present invention to provide a match pack holder which may be readily and easily secured in releasable firm engagement with a package of cigarettes or tobacco; to provide such a holder which is collapsible into a compact form when released from the package; to provide such a holder including means for firmly maintaining a pack of matches engaged therein; to provide a match holder arranged for operative association with a package of cigarettes and formed with a closure member for covering the cigarette removing opening in the package; and to provide a match holder for cigarette or tobacco packages which is simple in construction, inexpensive to manufacture and reliable in operation.

These and other objects, advantages and novel features of the invention will be apparent from the following description and the accompanying drawings. In the drawings:

Fig. 1 is a front elevation view of the match holder as applied to a cigarette package.

Fig. 2 is a side elevation view of the combination package and holder shown in Fig. 1.

Fig. 3 is an end elevation view of the match holder in its collapsed position.

Fig. 4 is a bottom plan view of the combination package and holder shown in Fig. 1.

Fig. 5 is a longitudinal sectional view on the line 5—5 of Fig. 4 looking in the direction indicated by the arrows.

Fig. 6 is a sectional view on the line 6—6 of Fig. 1.

Fig. 7 is a top plan view of a modification of the invention, including a closure for the cigarette removing opening of a cigarette package.

Fig. 8 is a front elevation view of the embodiment of the invention shown in Fig. 7.

Fig. 9 is an end elevation view of another modification of the invention match holder, shown in the collapsed position.

Generally speaking, the match packet holder of the present invention comprises a clip detachably engageable with the bottom fold of a

2

cigarette or tobacco package. A match holder or pocket is pivotally connected to the clip and, when the holder is attached to a package, the match holder lies against the front face of the package. When the holder is detached from the package, the match holding portion is collapsible into juxtaposed relation with the clip to provide a compact, easily carried unit. Means preferably are provided whereby the match holder automatically collapses into a compact form when removed from the package. Preferably, releasable means are provided on the clip for holding the latter firmly engaged with the package.

Referring more particularly to Figs. 1 through 6 of the invention, the invention device includes a clip 15 to which is pivotally secured a match holder or packet 20. Clip 15 includes a blade 25 insertable in the top or bottom fold 31 of a cigarette or tobacco package 30. Blade 25 is preferably tapered at its end, as indicated at 16, for easy insertion in the fold, and is integrally connected by a bight 17 to a bottom plate 18 which overlies the outer surface of a package fold 31.

Plate 18 is formed with an aperture 21 (see Fig. 2) through which extends a suitable clamping device 22 secured to blade 25. Clamping device 22 may be of any desired type. As shown more particularly in Figs. 3 and 5, it includes a spring blade 23 engaged by a pivotally mounted crank member 24 including an operating handle 26. In the released position shown in Fig. 3, handle 26 extends outwardly and spring 23 is in the free position. When handle 26 is moved to its inner position, shown in Figs. 1 and 5, it compresses spring 23 piercing the prongs 29 through the outer surface of package fold 31, whereby the fold is firmly gripped between blade 25 and spring 23. Clip 15 is thus maintained in firm engagement with fold 31 of package 30. Plate 18 also has another aperture 19, through which blade 25 may be observed to guide the blade into fold 31.

Plate 18 is formed with a right-angles flange 32 having portions shaped to provide hinge pintles 33. Pintles 33 receive a pin 34 extending through hinge pintles 35 on holder 20. A spring 36 normally resilient biases holder 20 clockwise, as viewed in Fig. 2, so that the device automatically collapses into the position shown in Fig. 3 when disengaged from the cigarette or tobacco package.

Match holder 20 comprises a rear wall 41, having forwardly extending flanges 42, and a front wall 43 integrally connected to rear wall 41 by a bottom wall 44. Front wall 43 is apertured, as at 45, to expose striking surface 51 of match book 50, thus providing upper edge portion 46.

Edge portion 46 is sprung inwardly adjacent its central section.

In operation, after the device of the invention is attached to a cigarette package, match book 50 is inserted into holder 20. Upon such insertion, striking surface 51 is exposed through aperture 45 so that the matches 52 may readily be struck on striking surface 51. At the same time, the upper edge of striking surface 51, adjacent its central portion, catches beneath the inwardly sprung portion 46 of front wall 43 so that the matches are firmly locked in holder or pocket 20. Match pack 50 may be released, however, if portion 46 is sprung outwardly, as by engagement with a fingernail or a tool.

The device shown in Fig. 1 thus comprises a compactly foldable match holder which is quickly and easily attached to and detached from a cigarette or tobacco package having the customary bottom fold 31. This bottom fold is found on practically all cigarette packages and most tobacco packages. The bottom fold has an advantage in securing a match holder to the package in that the clip portion of the holder is engaged with four layers of the package material, generally paper. Conversely, in the prior art devices, which have been engaged with other portions of the package, only one layer of paper maintains the holder in position. As a result, such prior art devices easily tore through the paper and became disengaged from the package. With the present device however, a much firmer attachment to the package is provided due to the four layers of paper comprising fold 31. Additionally, when the device is attached to the bottom fold, the center of gravity of the package is lowered, thus rendering the package more stable. In tobacco boxes having a movable closure on the bottom, the blade may be inserted underneath such closure to secure the match holder to the box, even though such closure is permanently secured in the closed position.

Additionally, bottom plate 18, which is generally rectangular in shape, prevents collapsing of the cigarette package when partly emptied, thus preventing damage to the remaining cigarettes by maintaining the bottom of the package in its original rectangular shape. Furthermore, spring 36 continually biases holder 20 inwardly against the front wall of the cigarette package, so as to maintain pressure on the remaining cigarettes 65 and thus prevent the same from flopping loosely around the package. Thereby, the cigarettes are kept in more attractive condition as the tobacco is maintained firmly therein and does not become loose, as frequently happens with cigarettes in a partially empty package. When the device is removed from the package, spring 36 automatically folds the device into the compact form shown in Fig. 3 thus presenting a small bulk, whereby the device may be easily carried in a pocket or handbag when not in use.

Figs. 7 and 8 illustrate a modified form of the invention in which the holder is attached to the top fold of a cigarette package and a closure is provided for the cigarette opening. As the device shown in Figs. 7 and 8 is identical with that shown in Figs. 1 through 6, except for the closure, the same reference characters have been used to designate identical parts. In this embodiment of the invention, a closure plate or door 60 is hingedly secured to plate 18 adjacent the outer side of an aperture 61 formed in the plate. A spring hinge 62 normally biases plate 60 into engagement with a tongue 63 projecting inwardly

into aperture 61. Aperture 61 is located adjacent the cigarette removing opening 64 provided by tearing a portion of the top fold of package 30 so that cigarettes 65 may be removed therefrom.

5 To remove cigarettes from the package, the inner edge of door 60 is engaged by a finger and the door opened, whereupon cigarettes 65 may be readily removed from package 30.

Fig. 9 illustrates a modified form of the invention in which spring 36 is eliminated from the hinge connection between holder 20 and clip 15. The hinge 66 used in this form of the invention is shaped so that clip 20 may only be moved from the position shown to a position perpendicular to clip 15. However, a spring clip 67 is secured to clip 15 and releasably engages the upper edge of back wall 41 of holder 20 to hold the device in collapsed position.

The described match packet holder provides a compactly foldable, easily engaged device which may be readily attached and detached from a package of cigarettes or tobacco. When detached, the device folds compactly into a small unit easily carried in a pocket or handbag. The device may be applied to any size or type of package including a bottom fold, such as customarily provided on cigarette packages. Due to the engagement of the clip portion of the device with such bottom fold, much more firm attachment to the package is provided as such bottom fold includes four layers of paper as compared to the single layer of paper on the remainder of the package. Prior art devices have generally been designed for attachment to a cigarette package elsewhere than at the bottom or upper fold, and have therefore been subject to ready disengagement due to tearing of the single layer of paper engaged by such devices.

The present device is usable with a standard size pack of cigarettes and also with a "king" size pack. Furthermore, the inwardly sprung bar or portion 46 of the front plate 43 of the match holder firmly locks the pack of matches in the holder so that accidental detachment is prevented unless the match pack is substantially destroyed.

While specific embodiments of the invention have been shown and described in detail to illustrate the application of the principles thereof, it will be understood that the invention may be otherwise embodied without departing from such principles.

What is claimed is:

1. For use with a package having an end fold, a match retainer comprising, in combination, clip means including a blade insertable in the end fold; and a match book holder secured to said clip means and arranged to lie against a wall of the package when said clip means is engaged in the end fold; said holder automatically folding against said clip means, when the latter is disengaged from the end fold, to form a compact, easily stored unit.

2. For use with a package having an end fold, a match retainer comprising, in combination, clip means including a blade insertable in the end fold; a match book holder secured to said clip means and arranged to lie against a wall of the package when said clip means is engaged in the end fold; said holder folding against said clip means, when the latter is disengaged from the end fold, to form a compact, easily stored unit; and means retaining said holder and clip means in such folded position.

3. For use with a package having an end fold, a match retainer comprising, in combination, clip

means including a blade insertable in the end fold; a match book holder secured to said clip means and arranged to lie against a wall of the package when said clip means is engaged in the end fold; and resilient means biasing said holder to fold against said clip means, when the latter is disengaged from the end fold, to form a compact, easily stored unit.

4. For use with a package having an end fold, a match retainer comprising, in combination, clip means including a blade insertable in the end fold; a match book holder secured to said clip means and arranged to lie against a wall of the package when said clip means is engaged in the end fold; and retaining means effective, upon insertion of a match book into said holder, to engage the edge of the striking surface of the book to retain the match book locked in said holder; said holder folding against said clip means, when the latter is disengaged from the end fold, to form a compact, easily stored unit.

5. For use with a package having an end fold, a match retainer comprising, in combination, clip means including a blade insertable in the end fold; releasable clamping means operative to engage the end fold to lock said clip thereto; and a match book holder secured to said clip means and arranged to lie against a wall of the package when said clip means is engaged in the end fold; said holder folding against said clip means, when the latter is disengaged from the end fold, to form a compact, easily stored unit.

6. For use with a package having an end fold, a match retainer comprising, in combination, clip means including a blade insertable in the end fold; releasable clamping means operative to engage the end fold to lock said clip thereto; a match book holder secured to said clip means and arranged to lie against a wall of the package when said clip means is engaged in the end fold; said holder folding against said clip means, when the latter is disengaged from the end fold, to form a compact, easily stored unit; and means retaining said holder and clip means in such folded position.

7. For use with a cigarette package having a wall and an end fold substantially perpendicular thereto, a match retainer comprising, in combination, clip means including a blade insertable in the end fold; a match book holder hingedly secured to said clip means and arranged to lie against such wall of the package when said clip means is engaged in the end fold; and resilient means biasing said holder against such package wall, as the package is emptied, to clamp the remaining cigarettes against loose movement in the partially empty package.

8. For use with a cigarette package having a wall and an end fold substantially perpendicular thereto, a match retainer comprising, in combination, clip means including a blade insertable in the end fold; a match book holder hingedly secured to said clip means and arranged to lie against such wall of the package when said clip means is engaged in the end fold; and resilient means biasing said holder against such package wall, as the package is emptied, to clamp the remaining cigarettes against loose movement in the partially empty package; said resilient means biasing said holder to fold against said clip means, when the latter is disengaged from the end fold, to form a compact, easily stored unit.

9. For use with a cigarette or tobacco package having an end fold, a match retainer comprising,

in combination, clip means including a blade insertable in the top end fold of the package and a plate integral with and parallel to said blade and adapted to lie outside the top fold; said plate having an aperture to provide for removal of cigarettes from an opening in the top of the package; a closure for such opening arranged in the aperture; and a match book holder hingedly secured to said clip means and arranged to lie

10 against a wall of the package when said clip means is engaged in the end fold; said holder folding against said clip means, when the latter is disengaged from the end fold, to form a compact, easily stored unit.

15 10. For use with a cigarette or tobacco package having an end fold, a match retainer comprising, in combination, clip means including a blade insertable in the end fold; and a match book holder hingedly secured to said clip means and arranged to lie against a wall of the package when said clip means is engaged in the end fold;

20 said holder folding against said clip means, when the latter is disengaged from the end fold, to form a compact, easily stored unit; said match

25 holder comprising substantially parallel front and rear walls forming a pocket to receive the striking surface of the match book and said front wall having an aperture to expose the match striking surface, the upper edge of the aperture being sprung inwardly to engage the upper edge of the striking surface and lock the match book in said holder.

30 11. For use with a cigarette or tobacco package having an end fold, a match retainer comprising, in combination, clip means including a blade insertable in the end fold and a plate integral with and extending parallel to said blade, said plate having a substantially perpendicular flange along one edge arranged to lie against a 35 face of the package; and a match book holder hingedly secured to said flange and arranged to lie against such package face when said blade is inserted in an end fold; said holder folding against said clip means, when the latter is disengaged from the end fold, to form a compact, easily stored unit.

40 12. For use with a cigarette or tobacco package having an end fold, a match retainer comprising, in combination, clip means including a blade insertable in the end fold and a plate integral with and extending parallel to said blade, said plate having a substantially perpendicular flange along one edge arranged to lie against a 45 face of the package; a match book holder hingedly secured to said flange; means retaining a match book locked in said holder; and resilient means biasing said holder to fold against said clip means, when the latter is disengaged from the end fold, to form a compact, easily stored unit.
